UNITED STATES PATENT OFFICE.

HILDING A. SJODAHL, OF CINCINNATI, OHIO.

DESIGN FOR A SHINGLE.

Application filed June 28, 1924. Serial No. 10,002. Term of patent 14 years.

To all whom it may concern:

Be it known that I, HILDING A. SJODAHL, a citizen of the United States of America, and a resident of Cincinnati, in the county of Hamilton and State of Ohio, have invented a new, original, and ornamental Design for a Shingle, of which the following is a specification, reference being had to the accompanying drawing, forming part thereof.

The figure is a plan view of a roofing shingle, showing my new design.

I claim:

The ornamental design for a shingle, as shown.

HILDING A. SJODAHL.
